PULL FOR FURNITURE OR THE LIKE

Melbourne F. Smith, Jr., Lenoir, N.C., assignor to Broyhill Furniture Factories, Lenoir, N.C., a partnership

Filed Apr. 15, 1963, Ser. No. 74,434

Term of patent 14 years

(Cl. D10—8)

Fig-1

The back of the pull for furniture or the like is substantially plain and unornamented.

I claim:

The ornamental design for a pull for furniture or the like, substantially as shown and described.
